DRUM MAJOR'S BATON

Frederick W. Miller, Chicago, Ill., assignor to
 C. G. Conn, Ltd., Elkhart, Ind., a corporation
 of Indiana

Application December 13, 1937, Serial No. 179,449

11 Claims. (Cl. 84—477)

This invention relates to drum majors' batons, and is illustrated in a relatively long baton having a generally spherical head at one end.

An object of the invention is to provide a baton of this type which is of pleasing appearance and the finish of which is protected against injury. To this end the head of the baton is provided with a cover of rubber material, the cover preferably being exteriorly formed with parallel ribs one of which is in the central plane of the head which extends perpendicularly relative to the baton axis. The cover extends beyond this central plane, so that it has to be stretched to pull it over the head and therefore maintains itself resiliently in place. The illustrated baton also has a cup-shaped cap of rubber material embracing a metal ferrule at its other end.

Another object is to provide a cover which will facilitate manipulation of the baton, such as bouncing it endwise on a pavement, without injury.

The above and other objects and features of the invention, including various novel combinations and arrangements, will be apparent from the following description of the illustrative embodiment shown in the accompanying drawing, in which:

Figure 1 is a side elevation of the baton body; Figure 2 is a side elevation thereof with the two end covers in place;

Figure 3 is a view partly broken away and on a larger scale, the lower half being the same as Figure 2 and the upper half being in vertical central section;

Figure 4 is a side elevation on a larger scale of a portion of a baton equipped with a modified form of end protection; and

Figure 5 is a section on the line 5—5 of Figure 4.

The baton proper, as shown in Figure 1, may consist of a highly-finished elongated generally-cylindrical body 10 (usually of wood), having at one end a metal cap or ferrule 12 mounted thereon (and shown as held by means such as a screw 14). Over the ferrule 12 is seated a cup-shaped protector of rubber material 18. The protector 18 is small enough so that it contracts resiliently upon the ferrule 12 when in place.

At its other end the baton body 10 is integrally formed with a generally-spherical head 20, which is preferably highly finished. This head is protected by a cover 22 of rubber material. This cover extends past the central plane which passes through the center of the head perpendicular to the axis of the body 10, and consequently must be

stretched to pull it over the head 20; it therefore resiliently grips the head 20 when it is in place.

Preferably the cover 22 is formed with a series of parallel encircling ribs 24, in planes perpendicular to the baton axis, and one of which is relatively wide and in the central plane of the head, so that when lying on its side the baton rests on this wide rib and on the protective cap 18. The ribbed mouth of this cover encircles head 20 and parallels the ribs 24.

The cover is formed at its axis with a protruding button 30, and with an adjacent rib 32 paralleling the ribs 24. The button 30 permits such manipulations as bouncing the baton endwise off a pavement, without injury, the rubber of the button flowing sufficiently into the space between the button and the rib 32 to give the necessary resilience. When the baton is leaned against something when not in use, it rests either on the button 30 or the rib 32.

The cover 18 and the cover 22 are readily removable, but are themselves of pleasing appearance and need not be removed when the baton is used.

In order to make the appearance of the assembly harmonious, the head 20 may be formed near its junction with the body 10 with an encircling shoulder 28 paralleling the ribs 24.

In the modification of Figures 4 and 5, in which corresponding parts have the same reference numerals plus 100, the main difference is that the cover 122 is provided with ribs 124 which extend longitudinally of the head 20 and are of more or less segmental form and which are evenly spaced circumferentially of the head. The ribs are close enough together so that the baton rests on them when lying on its side. It is obvious that this modification provides substantially the same protection to the baton as the previously described modification. Preferably the ribs are connected by thin webs of the rubber material, to make a complete cover.

While two illustrative embodiments have been described in detail, it is not my intention to limit the scope of the invention to those particular embodiments, or otherwise than by the terms of the appended claims.

I claim:

1. A drum major's baton or the like comprising an elongated baton body of generally cylindrical form having at one end a generally spherical head, and a rubber cover for said head extending past the central plane of the head perpendicular to the axis of the baton body and formed with a series of parallel ribs on its exterior and

one of which is in said central plane and having a ribbed mouth encircling said head and paralleling said ribs.

- 5 2. A drum major's baton or the like comprising an elongated baton body of generally cylindrical form having at one end a generally spherical head, and a rubber cover for said head extending past the central plane of the head perpendicular to the axis of the baton body.
- 10 3. A drum major's baton or the like comprising an elongated baton body of generally cylindrical form having at one end a generally spherical head, and a rubber cover for said head extending past the central plane of the head perpendicular to the axis of the baton body and formed with a series of parallel ribs on its exterior and one of which is relatively wide and arranged in said central plane and having a ribbed mouth encircling said head and paralleling said ribs.
- 15 4. A drum major's baton or the like comprising an elongated baton body of generally cylindrical form having at one end a generally spherical head, and a rubber cover for said head extending past the central plane of the head perpendicular to the axis of the baton body and formed with a series of parallel ribs on its exterior and one of which is in said central plane and having a ribbed mouth encircling said head and paralleling said ribs, said head having a peripheral shoulder adjacent said body and paralleling the ribs and the edge of said cover.
- 20 5. A drum major's baton or the like comprising an elongated baton body of generally cylindrical form having at one end a generally spherical head, and a rubber cover for said head extending past the central plane of the head perpendicular to the axis of the baton body and formed with a series of parallel ribs on its exterior and one of which is relatively wide and arranged in said central plane and having a ribbed mouth encircling said head and paralleling said ribs, said head having a peripheral shoulder adjacent said body.
- 25 6. A drum major's baton or the like comprising an elongated baton body of generally cylindrical form having at one end a generally spherical head, and a rubber cover for said head extending past the central plane of the head perpendicular to the axis of the baton body and formed with a series of circumferentially spaced longitudinal segmental ribs.
- 30 7. A drum major's baton having at its end a generally spherical head provided with a cover of rubber material having a protruding button of such material at the end of the baton.
- 35 8. A drum major's baton having at its end a generally spherical head provided with a cover of rubber material having a protruding button of such material at the end of the baton, and having a rib encircling said cover adjacent said button in a plane perpendicular to the baton axis.
- 40 9. A drum major's baton having at its end a generally spherical head provided with a cover of rubber material having a protruding button of such material at the end of the baton and having a rib encircling said cover adjacent said button in a plane perpendicular to the baton axis, and also having a rib paralleling the first rib and arranged in the central plane of said head.

and paralleling the ribs and the edge of said cover.

6. A drum major's baton or the like comprising an elongated baton body of generally cylindrical form having at one end a generally spherical head and a rubber cover for said head extending past the central plane of the head perpendicular to the axis of the baton body and formed with a series of parallel ribs on its exterior and one of which is in said central plane.

7. A drum major's baton having at its end a generally spherical head provided with a cover of rubber material having a protruding button of such material at the end of the baton.

8. A drum major's baton having at its end a generally spherical head provided with a cover of rubber material having a protruding button of such material at the end of the baton, and having a rib encircling said cover adjacent said button in a plane perpendicular to the baton axis.

9. A drum major's baton having at its end a generally spherical head provided with a cover of rubber material having a protruding button of such material at the end of the baton and having a rib encircling said cover adjacent said button in a plane perpendicular to the baton axis, and also having a rib paralleling the first rib and arranged in the central plane of said head.

10. A drum major's baton or the like comprising an elongated baton body of generally cylindrical form having at one end a generally spherical head and a rubber cover for said head extending past the central plane of the head perpendicular to the axis of the baton body and formed with a series of circumferentially spaced longitudinal segmental ribs.

11. A drum major's baton having at its end a generally spherical head provided with a cover of rubber material having a protruding button of such material at the end of the baton, and having longitudinal segmental ribs extending from said button.

FREDERICK W. MILLER.
